REMOVABLE BURNER ASSEMBLY

Hans Stierlin, Rainweg 15, Schlieren, Zurich, Switzerland
Filed Nov. 17, 1958, Ser. No. 774,205

Claims priority, application Switzerland Nov. 18, 1957
8 Claims. (Cl. 158—4)

This invention relates to oil burning ovens or furnaces of the open pot burner type and more particularly to the construction of the burner assembly thereof.

An object of the invention is to facilitate the servicing, repairing and cleaning of oil burners of the pot type by facilitating access to the elements of the burner assembly.

A further object of the invention is to provide oil ovens of which the burner and its associated elements may be removed from the oven or furnace per se without uncoupling threaded fittings or disconnecting wires of the electric system thereof.

Still another object is to construct the burner per se, the fuel tank, and the blower of an oil burning oven or furnace as a removable and interchangeable unit in order to expedite restoration of the oven or furnace being cleaned or requiring repairs, back into service.

The oil burner of oil furnaces of the pot type must be removed from the furnace or oven per se for inspection, adjustment, cleaning and repair thereof. Of necessity, the burner has an oil line to the fuel regulator and the tank, which line must be disconnected when dismantling the burner of prior art furnaces. To permit of such disconnection, the oil line is attached to the burner by means of threaded fittings which can be loosened with tools or by means of large wing nuts. The burner itself can be removed from the main body of the furnace or oven by loosening screw fittings or opening bayonet or other type connectors. If the burner is provided with a fan, the electric connections thereto must also be removed.

In practice, the disconnection of so many lines and the necessity of restoring all of them has resulted in serious difficulties, as also defects in the reassembled burner aggregate. Frequently such work is done by personnel not fully acquainted with the particular burner. Thus it happens that, on reassembly of the burner, the oil line drips, or the electrical connections are faultily or wholly incorrectly restored, so that the burner cannot operate, or operates defectively, or that fouling, dirtying, or even fires, result from oil drippings. Furthermore, prolonged work upon the always dirty burners makes for dirtying work by the serviceman. And if, in addition the burner controls are automatic, dismantling and reassembly of the burner is so complicated, that only specially trained personnel should undertake such work.

There are prior known oil furnaces of the pot type in which the vaporizer-burner is made pivotable for facility in lighting and cleaning it. The connection between the float valve control and the vaporizer is by a heat-resistant tube of synthetic material; but even in such construction when the furnace is to be dismantled because repairs are required, the burner assembly must still be completely disassembled, including the disconnection of many, more or less difficultly accessible, connecting points in the lines, pipes and cables. With furnaces of such construction, on the occurrence of a major fault, the furnace is frequently out of operation for several hours, which, of course, is not at all desirable.

Also prior known are non-automatically controlled oil furnaces of the pot type in which a pivotally disposed aggregate, consisting of the bottom member of the pot burner and the oil reservoir, as also of some rigid connections therebetween, may be lifted from the furnace. In such construction, the oil tank is disposed externally of the furnace. Lifting the aggregate out of and reinserting it into the pivoted forks on which it is supported

2

is, however, quite burdensome. In still another prior known type furnace, the burner aggregate is disposed telescopically in the furnace, the aggregate including the controls being connected to an external tank by a severable connection, which may cause oil dripping, as above explained. The electrical lines must also be disconnected from the supply line in this construction before the aggregate can be withdrawn from the furnace. Furthermore, in such construction, which is simply pushed back into the furnace, the sealing problem of the pot burner to the flame chamber is by no means satisfactorily solved.

The furnace construction according to the instant invention avoids all of the foregoing shortcomings and is an interchangeable unit consisting of the elements of the burner assembly which is characterized in that the entire unit, including a base which forms the oil tank, may be raised and lowered, the burner shell being resiliently supported on the oil tank so that the unit, after it has been lowered, may be pulled from the furnace.

Two illustrative embodiments of the invention will now be described and explained in detail with the aid of the annexed drawing, in which:

FIGURE 1 shows the section of the first embodiment of the oil oven of the pot type of my invention, showing the burner assembly in operative condition; and

FIGURE 2 shows the corresponding section of the second embodiment, but with the burner group out of the operative condition.

In the fully automatic oil oven of FIGURE 1, the flame chamber 1 is provided with a smoke stack or chimney (not shown) and with a body 3 constituting a single structural unit within the oven having vertical and horizontal walls forming a hollow body. An oil tank 4 forms a supporting base for the entire interchangeable burner assembly, a pot burner 6 being supported by springs 14 thereon, together with the other elements required for automatic operation. Each of the springs 14 is housed in an open-ended vertical cylinder 14A affixed to the top of tank 4 and is braced against the lower end of piston 15 within such cylinder, the upper ends of the pistons supporting the pot burner assembly. Upward movement of each of pistons 15 is limited by the engagement of an outwardly extending annular shoulder at the lower end of the piston engaging an internally extending flange 14B at the top end region of its enveloping cylinder 14A. At the forward portion of tank 4, on a forwardly projecting tongue, a lever 10 having a long and a short arm and vertically pivotable, is journaled therein, the short arm being provided with rollers 11 at its free end which ride on the bottom horizontal wall of the oven body. The rear portion of the tank, which inclines downwardly from front to rear, is also supported by rollers 11' on straps integral with the tank which rollers 11' likewise are in rolling contact with the bottom wall of the oven body. Rollers 11 and 11', which may run on a track (not shown) on the bottom horizontal wall of the body, permit the burner assembly readily to be pulled from within, and to be pushed back into, the interior of the oven body. 3. Obviously, slides may be used instead of rollers. When lever 10 is moved upwardly in the direction of the arrow (FIG. 2), the entire burner assembly moves upwardly (FIG. 1), pivoting about the shaft of rear rollers 11' as the front rollers are brought from below the front bottom of the tank to forward of the tank by such movement of lever 10. In so doing, the upper rim region of the cylindrical wall 6A of the pot burner 6 is moved into a conical annular groove 12 of a cast ring forming the bottom of flame chamber 1. Pot burner 6 has a centrally dished bottom 6B from the periphery of which the integral cylindrical wall 6A extends upwardly, wall 6A having a plurality of air inlet ports 6C. An open top cylindrical casing 6D having its upper end sealed to the

upper region of the cylindrical wall 6A very close to the upper rim thereof, surrounds cylindrical wall 6A. A blower fan is positioned below dished bottom 6B of the burner. Springs 14 continuously and tightly press the upper rim region of pot burner 6 against the cast ring 13. The fuel feed element is a scoop conveyor 16 driven by an electric motor 17 which may be of the variable speed or synchronous types, the bucket or scoop conveyor and the pot burner 6 being connected to each other by oil lines 18 and 19. Within the pot burner 6, and extending from the bottom thereof, there is disposed an electrical ignition device 22 connected by line 23 to a distributor 25, while fan or blower 26 is disposed below the pot burner. The fan is driven by a motor 27 connected by line 28 to the distributor 25. The air blown by fan 26 through ports 6C of the burner cylindrical wall is thus mixed with the supplied oil in the mixing chamber formed by the burner dished bottom and its integral cylindrical wall. The fuel oil standpipe 30 is provided with a drain valve 31 having a bimetal strip 32 at the upper end of its valve rod for control purposes thereof. Electrical connection of the oil furnace to the line is by means of a plug 42 and a coupling 33, 33'. The details of the oil burner per se and its fuel supply with the standpipe, drain valve and bimetal strip, are described in detail in my copending application for patent, Serial Number 697,219, filed November 18, 1957, for "Pot Type Oil Burner," which description is herewith incorporated by reference. In the inserted position of the assembly, the tank rear wall is against a resilient stop 34 on the rear vertical wall of the oven body. A door 35 in the oven body front vertical wall serves the purpose of access to the assembly and to lever 10.

Interchange of the burner assembly is accomplished as follows: Upon opening door 35, access to lever 10 is possible. The upper and handle end of lever 10 is pulled forward and then lowered, thus swiveling the front rollers 11 to the rear causing the assembly to be lowered. In so doing, the upper rim of the cylindrical wall of the pot burner 6 moves out of the conical groove 12 of ring 13 and the coupling 33, 33' is opened. Thus the assembly can be completely withdrawn from the oven body and, if repairs are required, may be replaced by an operating-ready replacement assembly. On reintroduction of a burner assembly into the oven body, the assembly is pushed back against stop 34 and lever 10 is restored to the vertical position as shown in FIGURE 1 and the oven is restored to operativeness, the upper rim of the cylindrical wall of the burner being continuously pressed against ring 13 by support springs 14. If the actuation of lever 10 back to its vertical position should be forgotten, the oven door 35 cannot be reclosed, calling attention to the oversight. When the oil tank 4 requires refilling, the burner assembly is pulled out, cover 4a of the front portion of the tank is removed and the tank refilled, the cover replaced, and the tank is pushed back into the oven body. Then the mixing chamber is sealed to the flame chamber by restoring the lever to its vertical position, the oven door being thereupon closed.

In the embodiment shown in FIGURE 2, the room oven is connected by a fuel line 38 to an externally positioned oil reservoir. A gear pump 36 conveys the oil from the reservoir by way of lines 38 and 37 to the daily tank 4, with lines 37 and 38 connected to each other by way of a readily severable connector fitting. For this purpose, line 37 has a flange at its end provided with a soft rubber packing 39 on which packing a counter-flange 40 at the end of line 38 presses. This severable connection is positioned above the maximum level of oil possible in the daily tank so that when it is severed no oil can flow therefrom. The withdrawal and insertion of the burner assembly in this embodiment are the same as above described for the FIGURE 1 embodiment. The lever to be actuated in the withdrawal and reinsertion of the burner aggregate of this embodiment is likewise so

arranged that the oven door cannot be closed if the burner is not in operative condition. Thus, operation of the oven as long as the cylindrical wall of the seal between the burner and the oven per se is open, is totally impossible. In the case of assemblies which are not connected to oil reservoirs by way of an oil conveying pump and into which oil must periodically be refilled, such refilling can be substantially simplified by pulling the burner assembly out to a greater or lesser extent, as may be required. Thus, as above stated, the embodiment of FIGURE 1 need be pulled out only enough to permit removal of cover 4a, while if the embodiment of FIGURE 2 would have a cover over packing flange 39 and would then have to be pulled out that far to remove such cover. In so doing it will readily be possible to fill the tank without permitting even traces of oil to overflow, which is important because even a single drop of oil on a wooden floor, for example, will for days generate an unpleasant smell of oil.

Cleaning such an oven according to the invention may be as follows: The chimney sweep first cleans the oven body and the flame chamber of soot and dust, both of which are initially swept into the pot burner. On completion of such sweeping, the pot burner by actuation of the hand lever, and without severing other connections, is moved from the oven body and the entire burner assembly withdrawn from the body, where all dirt and foreign matter is now readily removed from the pot burner. Even more hygienically and in cleaner fashion, this work can be done as follows: The chimney sweep first withdraws the burner assembly from the oven body, and then introduces a paper bag 41 into the pot burner, after which he pushes the assembly back into its operative position within the body and cleans the upper region of the oven. Dust and finely divided soot, which occur only in this region, fall down into the bag. By again withdrawing the burner assembly from the oven, such dirt, which is mainly responsible for the unwanted soiling of living quarters, may be completely removed with-out further manipulation than removing the bag. Only thereafter are the coarser grained impurities removed from the pot burner.

If a cleaning or repair of the pot burner of such construction were to be undertaken in the usual prior manner, namely, by disconnecting all the connections between the pot burner and the other parts of the burner assembly, appropriate threaded connectors, severable for such purpose, would have to be provided. This must be avoided in view of the poor accessibility of the burner and the danger that in the course thereof the fan 26 or the motor 27 might be damaged. Furthermore, repair of the bucket conveyor mechanism would be extremely difficult in the prior forms of construction due to its poor accessibility.

In dismantling ovens due to defects in the burner assembly of the instant invention, the procedure is as follows: The oven consists of three units readily severable from each other, namely, the oven body per se, the burner assembly, and the electrical controls including thermostats, etc. An interchangeable replacement unit for each 60 the burner assembly and the control elements is brought by the serviceman when making a service call. As a first step, by a simple severance of two plug connections, the control elements are removed from the oven and replaced by the spare control elements unit. If the oven now operates, the repair has been completed. If it should not now operate, the original control elements unit is again replaced, and now the entire burner assembly replaced by the spare burner assembly. In that there can hardly be a defect in the oven body per se, the oven is thereby restored to operativeness and the repair is finished. The unit found defective on such procedure can be forwarded to an appropriately equipped repair shop, where eventually it is restored to operativeness by trained experts and can be used as a replacement unit for another oven.

What I claim is:

1. A fully automatic oil oven having vertical and horizontal walls forming a hollow body, a flame chamber spatially fixed within the body and having a centrally apertured bottom, a door in the lower region of a vertical wall of the body, a unitary assembly comprising a pot-type mixing chamber open at its top, electrical ignition means positioned in the bottom interior region of the mixing chamber, a closed fuel oil tank, a fuel oil passageway from the tank to the interior of the mixing chamber, spring means for supporting the mixing chamber on the tank and for yieldably sealing the upper end of the mixing chamber to the bottom of the flame chamber about the central aperture thereof, an electrical conductor, a severable connector having a first and a second element of which the first element is supported on the tank and is connected to the ignition means by the conductor, the second element of the connector being on the body in registering position with the first element for connection to a source of electrical potential, means on the unitary assembly for lowering and raising the unitary assembly and normally maintaining the mixing chamber sealed to the flame chamber and the two elements of the connector in engagement when the unitary assembly is in its fully inserted and oven operative position within the body, said means being manually operable in one direction to lower the unitary assembly within the body and to simultaneously unseal the mixing chamber from the flame chamber and to disconnect the two elements of the connector from each other and in the other direction to raise the unitary assembly and to simultaneously seal the mixing chamber to the flame chamber and to connect the two elements of the connector to each other, and means on the unitary assembly facilitating movement of the unitary assembly in lowered position longitudinally of itself.

2. The oil oven according to claim 1 in which the means for lowering and raising the unitary assembly is an elongated lever pivoted adjacent to the bottom of the tank and having a longer upper and a shorter lower arm, the free end of its lower and shorter arm being provided with a roller engaging the horizontal wall of the walls forming the oven body constituting the bottom of the oven body, the forward end of the unitary assembly when fully inserted into the oven body being at a distance from the front vertical wall of the walls forming the oven body, the lever on being deflected forwardly with its upper and longer arm toward the horizontal lowering at least the front portion of the assembly sufficiently to disengage the mixing chamber from the bottom of the flame chamber, and the lever longer arm being of a length greater than said distance between the assembly and the front vertical wall of the oven.

3. The oil oven according to claim 2 in which the bottom of the tank is inclined downwardly from the front to the rear of the tank and the means facilitating longitudinal movement of the unitary assembly in lowered position comprises a pair of rollers journaled at the end region of the tank the more remote from the front vertical oven wall.

4. The oil oven according to claim 2 in which the means facilitating moving the unitary assembly longitudinally comprises a pair of rollers on a transverse axle on the bottom of the tank at its region remote from the region at which the elongated lever is pivoted.

5. The oil oven according to claim 4 in which when the unitary assembly is in the operative position within the oven body the bottom of the tank inclines downwardly from its end adjacent to the oven door to its end remote from the door and the elongated lever is pivoted at the tank region the more adjacent to the oven door so that on the forward deflection of the lever the tank is pivoted about the transverse axle of the pair of rollers.

6. The oil oven according to claim 1 in which the spring means supporting the mixing chamber comprises a cylinder supported on the tank, an internal annular flange

integral with the upper end of the cylinder, a piston having an enlarged head within the cylinder, and a spring biasing the piston head upwardly toward engagement with the flange, the position of the seal between the mixing and flame chambers above the piston head preventing the engagement when the unitary assembly is in the operating position within the body while allowing such engagement on downward movement of the unitary assembly, the continued downward movement after such engagement breaking said seal, on operation of the unitary assembly lowering and raising means in said one direction.

7. A fully automatic oil oven comprising vertical and horizontal walls forming a hollow oven body, a flame chamber having a centrally apertured bottom, an annular groove in the flame chamber bottom concentric with the central aperture therethrough, an oven door in the vertical wall of the oven body constituting the front of the oven body, a stop on the internal face of the vertical wall of the oven body constituting the rear wall of the oven body and opposite the door, an electrical socket for connection to a source of electrical energy supported in said rear vertical wall, a unitary assembly for complete insertion into the interior of the oven body and comprising a pot having a cylindrical wall, an electrical ignition plug centrally disposed at the bottom of the pot the cylindrical wall of the pot defining a plurality of air intake apertures, a cylindrical casing closed at its bottom and of a diameter greater than that of the cylindrical wall of the pot disposed about the pot and taperingly joined at its top to a region close to the top of the cylindrical wall, the bottom of the cylindrical casing being spaced from the bottom of the pot, a fan in the region defined between the bottom of the pot and the bottom of the cylindrical casing, an electric motor for driving the fan, an enclosed fuel tank positioned within the oven body between said front and rear vertical walls and having a bottom inclined downwardly from its end adjacent to but spaced from the oven door to the end remote therefrom, means for supplying oil from the tank to the pot, an electrical distributor supported on an upper exterior portion of the tank, electrical connections from the distributor to the ignition plug and motor respectively, an electrical connector plug connected to the distributor and supported on the exterior of the wall of the tank remote from the oven door, spring means supporting the assembly on the tank top, the spring means including at least one cylinder supported on the top wall of the tank and having an internal flange at its top defining a central aperture, a piston extending through the central aperture of the flange and engaging the bottom of the cylindrical casing, the piston having a shoulder at its lower end region within the cylinder, which shoulder at maximum elevation of the piston engages the internal flange, and a spring within the cylinder braced between the top wall of the tank and the piston shoulder to bias the piston upwardly, first roller means attached to the tank bottom at a region thereof remote from the door and engaging the bottom horizontal wall of the oven body, a lever pivoted to the tank end adjacent the oven door at a region adjacent to the tank bottom, the lever having a long arm upwardly and a short arm downwardly of the region at which it is pivoted, second roller means at the free end of the short arm, the second roller means engaging the bottom horizontal wall of the oven body so that when the lever is in a normal vertical position the spring presses the upper end of the cylindrical wall tightly into the annular groove in the flame chamber bottom and the piston shoulder is below and spaced from the internal flange of the cylinder and when the lever is moved forwardly away from the tank toward the horizontal the lever end of the tank is lowered sufficiently about the first roller means as a pivot to permit the spring to force the piston upwardly to engage the internal flange of the cylinder preventing further upward movement of the cylindrical wall, the downward movement of the front region of the tank caus-

ing the top of the cylindrical wall now to leave the groove, and the connector plug to separate from the socket, and permitting withdrawal of at least the front end region of the unitary assembly through the oven door, while on reinsertion into the oven body of the withdrawn unitary assembly the remote end of the tank strikes the stop and the subsequent restoration of the lever to the vertical position reconnects the connector plug and socket and restores the upper end of the cylindrical wall into the annular groove.

8. The fully automatic oil oven according to claim 7 in which the long arm of the pivoted lever is of such greater length than the distance between the adjacent end

5
8
of the tank and the oven door as to permit closure of the oven door only when the burner assembly is in its elevated position sealing the upper end of the cylindrical wall in the annular groove.
